DESIGN FOR A TOY HORSE

Ilse von Schenk, New York, N. Y.

Application April 16, 1941, Serial No. 100,409

Term of patent 7 years

To all whom it may concern:

Be it known that I, Ilse von Schenk, a citizen of the United States, residing at New York city, in the county of New York and State of New York, have invented a new, original, and ornamental Design for a Toy Horse, of which the following is a specification, reference being had to the accompanying drawing, forming part thereof.

In the drawing—

Fig. 1 is a side elevational view of a toy horse showing my new design;

Fig. 2 is a top plan view thereof;

Fig. 3 is a front perspective view.

I claim:

The ornamental design for a toy horse, as shown.

ILSE VON SCHENK.
